(57) **CLAIM**

We claim the ornamental design for a panel for appliance, as shown and described.

DESCRIPTION

FIG. 1 is a perspective view of a first embodiment of a panel for appliance, showing our new design;
 FIG. 2 is a front elevational view thereof;
 FIG. 3 is a rear elevational view thereof;
 FIG. 4 is a left side elevational view thereof;
 FIG. 5 is a top plan view thereof; and
 FIG. 6 is a bottom plan view thereof;
 FIG. 7 is a perspective view of a second embodiment of a panel for appliance;
 FIG. 8 is a front elevational view thereof;
 FIG. 9 is a rear elevational view thereof;
 FIG. 10 is a left side elevational view thereof;
 FIG. 11 is a top plan view thereof; and,
 FIG. 12 is a bottom plan view thereof.

Broken lines are for illustrating unclaimed portions of the panel for appliance and/or for illustrating an environment related to the claimed design; the broken lines form no part of the claimed design. The right side elevational view of the first embodiment of the panel for appliance is a mirror image of the left side elevational view shown in FIG. 4. The right side elevational view of the second embodiment of the panel for appliance is a mirror image of the left side elevational view shown in FIG. 10.
